* cited by examiner

Primary Examiner — Mary Ann Calabrese*(74) Attorney, Agent, or Firm* — Banner & Witcoff, Ltd.(57) **CLAIM**

The ornamental design for a display screen with icon, as shown and described.

DESCRIPTION

The FIGURE is a front view of a display screen with icon showing the new design.

The broken line showing of the remainder of the display screen is for environmental purposes only and forms no part of the claimed design.
